UNITED STATES PATENT OFFICE.

ALFRED MAYER, OF DULUTH, MINNESOTA.

SCREEN.

Application filed March 5, 1927. Serial No. 172,938.

This invention relates to screens and has special reference to a screening mechanism particularly adapted for use in the screening of material used in the making of concrete.

The principal object is to provide a device of this character of simple construction and efficient in operation.

Other objects and advantages of the novel arrangement will appear in the further description of the invention.

Referring now to the accompanying drawing, forming part of this application, and wherein like reference characters indicate like parts:

Figure 1 is a central vertical section through one of the improved machines; and

Figure 2 is a section on the line 2—2, Fig. 1.

The embodiment here illustrated comprises a fabricated, frusto-pyramidally shaped structure indicated at 1, the bottom members 2 of which are slightly upturned at both ends to act as runners or shoes for convenience in transporting same, and these members are preferably of angle iron. The upper horizontal side members 3 are of channel iron and at one end arcuate in form, being turned downwardly as at 4 with their lower extremities terminating adjacent the end wall or the upright support 1, and which end wall is preferably entirely covered with a bulkhead or apron 5.

A hopper 6 having flaring end walls and vertical side walls is mounted within the channels 3 by having depending members 7 from the two opposite sides thereof in which are mounted the two cross shafts or axles 8 mounted upon wheels or rollers 9 at the opposite ends thereof, said wheels or rollers being in diameter approximately equal to the depth of the channels 3 and designed to travel within same. The depending members 7 are rigidly fixed to the angle 10 which surrounds the bottom of the hopper and in which the latter is held by suitable short bolts 11 passing through the smaller angle iron rigidly fixed to the inner lower marginal edge of the hopper 6. The screen in the bottom of the hopper, indicated at 13, is installed intermediate of the angles 10 and 12 so that by removing the bolts 11 the hopper may be raised and the screen changed when desired in the most convenient manner possible.

A cross angle or stop 14 is installed trans-

verse the rearmost ends of the channels 3 so as to prevent the hopper carriage from being pulled out of its track, and in operation the material to be screened is thrown in 60 the hopper and the latter reciprocated by hand, or power if preferred in the larger type of machine. Then when one filling or charge of the hopper has thus been screened or sifted the hopper is pushed to 65 the forward arcuate end of the track or tramway when the wheels following such curved portion will dump the hopper eventually to vertical position as shown in dotted lines Figure 1. During this dumping operation, as the forward axle 8 of the car proceeds it will engage the two upright fingers 15 mounted on a spring controlled shaft 16 suitably mounted transverse the arcuate ends of the channels 3; the spring 70 being so applied to this shaft in any desired manner as to normally bias the hopper in upright position as shown in Figure 1. In this manner provision is made for the easy return of the dumped hopper as the spring 75 controlled shaft with its fingers engaging the axle of the car will tend to return same to its horizontal position and thereby assist in such return, which obviously may be made more or less forcible as desired. 80

It is evident that the device may be made in any desired size or height so that for example wagons or tram-cars may be operated therebeneath, or such a device may be installed adjacent a mixing box or machine 90 with chutes leading therefrom for convenience and adaptability and that the device may be modified somewhat from that here illustrated without departing from the spirit of the invention. 95

Having thus described my invention, what I claim and desire to secure by Letters Patent, is:

1. A device of the character described comprising in combination an upright fabricated structure, a horizontally disposed track traversing the upper portion of the structure, said track comprising spaced channel irons facing each other one end of same terminating downwardly and arcuately towards the structure forming a dumping portion of the track, a screening hopper reciprocally mounted within the track and selectively operable within either the horizontal portion thereof for screening purposes or the dumping portion thereof. 105
2. A device of the character described

comprising an upright fabricated structure, a track traversing the upper portion of the structure, said track comprising spaced channel irons facing each other one end of same terminating downwardly and arcuately towards the structure, a hopper mounted within the track and operable therewithin, a shaft disposed axially of the arcuate portion of the track and carrying a spring for engagement with the hopper for automatically returning same from the arcuate portion.

3. A device of the character described comprising an upright fabricated structure, a horizontally disposed track traversing the

upper portion of the structure, said track comprising spaced channel irons facing each other one end of same terminating downwardly and arcuately towards the structure forming a dumping portion of the track, 20 a screening hopper reciprocally mounted within the track and selectively operable within either the horizontal portion or dumping portion, a shaft disposed axially of the dumping portion of the track and carrying a spring for engagement with the hopper for automatically returning same from dumping to horizontal position. 25

In testimony whereof I affix my signature.
ALFRED MAYER.
